UNITED STATES PATENT OFFICE.

PETER E. SHIRK, OF SPRING GROVE, ASSIGNOR, BY DIRECT AND MESNE ASSIGNMENTS, TO WILLIAM H. LAWSON, OF HONEY BROOK, PA.

THILL-COUPING.

SPECIFICATION forming part of Letters Patent No. 247,699, dated September 27, 1881.

Application filed February 7, 1881. (Model.)

To all whom it may concern:

Be it known that I, PETER E. SHIRK, of Spring Grove, in the county of Lancaster and State of Pennsylvania, have invented certain

5 Improvements in Thill-Couplings, of which the following is a specification.

The object of this invention is to produce a coupling which shall permit the ready attachment and detachment of the thills, which shall 10 be noiseless in action, and which shall be cheap and simple in construction; and to this end it consists in a construction and combination of the various parts hereinafter described, embracing, primarily, the combination of a divided head, a rubber cushion therein, and an eccentric or cam lever for fastening the head together.

Referring to the accompanying drawings, Figure 1 represents a vertical central section 20 through my device, with the parts in an operative position. Fig. 2 is a section of the same, showing the head opened and the end of the thill detached therefrom; Fig. 3, a vertical cross-section upon the line $x-x$ of Fig. 1.

25 Referring to the drawings, A B represent the head or body of the coupling. The main portion A is constructed in one piece with a clip, a, to embrace the axle, as usual, and with two parallel forwardly-projecting jaws, b. The clip a is made, as usual, with two downwardly-extending threaded shanks, c and d, to receive a bottom plate, e, and the two fastening-nuts f, by means of which the clip is drawn against and held firmly upon the axle.

35 As shown in Figs. 1 and 2, the stem d is elongated and extended downward to receive and hold the lower portion, B, of the body, which is perforated to fit over the same. The lower end of the stem d is provided with a cam- 40 lever, C, forked to embrace the stem, and pivoted thereto, as shown at f': The forward end of this lever is provided with an eye or loop to receive a safety-strap, which may be used to connect it with the thills, in order to prevent 45 the escape of the latter in the event of a break-age of the parts.

The lever C is constructed in such manner that when its forward end is turned upward to a normal position (represented in Fig. 1) the 50 eccentric end of the lever holds the two parts

A B of the head firmly and rigidly together, the eccentric end of the lever locking past the center in such manner that it has no tendency to unlock when the head is subjected to strain. When the end of the lever is turned downward 55 it permits the lower section of the head to fall away from the upper portion, A, in order to permit the introduction or removal of the thill-iron.

As shown in Figs. 2 and 3, the inner faces 60 of the arms b are cut away on the under side in such manner as to form two hook-shaped recesses, h, to receive the journals or trunnions i, formed on the sides of the thill-iron D. The thill-iron D is introduced and removed through 65 the end of the head, between the two arms, and is applied from the under side, as indicated by the arrow in Fig. 2.

The lower section, B, is made of such form as to fit snugly within the recess portion of the 70 upper section and closely embraces the under side of the trunnions of arm D, as represented in Figs. 1 and 2.

E represents a rubber or equivalent elastic cushion located in the head behind the thill-iron, and retained in place by projections or shoulders in the head, as shown in Fig. 1. The construction of the parts is such that the necessary compression of the rubber to secure a 75 close action of the parts is secured by the action of the lever C, thus avoiding the use of special tools or devices commonly employed to press rubber.

It will be noted that the lower section, B, of the body abuts against and serves to lock the 85 two nuts by which the clip is held, thus effectually preventing their loss from vibration or other causes.

Having thus described my invention, what I claim is—

1. The combination of the shouldered body A, provided with the depending neck d, the bottom plate, B, mounted on and around the neck, and the eccentric lever C, pivoted to the neck below the plate, as described and shown. 95

2. The combination of the stationary body A, provided with the shoulders to receive the thill-iron, and the depending neck, the thill-iron, the rubber block, the bottom plate, B, and the eccentric lever pivoted to the neck below 100

the plate and arranged to lock past the center, as described and shown.

3. In combination with the head-section A, recessed on the inner and under side, as shown at h, the lower section, B, fitting within the under side of the head and inclosed thereby, as described and shown.

4. In combination with the head-section A, having the clip to embrace the axle, the base

plate, and nuts, and section B, serving the two-fold purpose of securing the thill-iron and of locking the nuts in place, substantially as shown.

PETER E. SHIRK.
